UNITED STATES PATENT OFFICE

OTTO KURZ, OF ST. GEORGEN/SCHWARZWALD, GERMANY, ASSIGNOR TO CHRISTIAN STEIDINGER, OF ST. GEORGEN/SCHWARZWALD, GERMANY

SPEED GOVERNOR FOR GRAMOPHONES

Application filed November 10, 1928, Serial No. 318,482, and in Germany May 18, 1928.

This invention relates to an arrangement for regulating the speed of gramophones. In this arrangement the adjusting lever is connected to a bearing in the top plate of the casing. In this bearing a hollow body is inserted from above and frictionally connected therewith. This hollow body is further connected with a plate having a nose engaging in a slot in the angle piece carrying the 5 brake block. This angle piece is guided on the top of the gramophone casing so that, on the adjusting lever being turned, the nose on the plate attached thereto displaces the angle piece carrying the brake block and moves 10 the brake block towards or away from the brake disc of the centrifugal governor.

This adjusting lever may also be used for arresting the rotation of the turntable of the gramophone irrespectively of the driving mechanism. For this purpose the lever has a bent up end and is displaceable longitudinally radially to the driving axle of the gramophone and on being displaced towards the axle its bent up end engages with the outwardly bent end of a spiral spring gripping around the hub of the turntable and thereby arrests the rotation of the turntable. If this lever is again moved outwardly in radial direction without changing the position of the sleeve controlling the position of the governor brake block in relation to the brake disc, the turntable on being released will again be driven at the same speed as before.

An embodiment of the invention is illustrated, by way of example, in the accompanying drawing, in which

Fig. 1 is a section on line A—B of Fig. 2.

Fig. 2 is a part top plan view of the regulating mechanism.

Fig. 3 is a part longitudinal section on line E—F of Fig. 2.

Fig. 4 is a horizontal section on line G—H of Fig. 3.

In a cut out portion of the top plate of the casing a bearing 6 is arranged, held on the cover plate 2 of the driving mechanism by means of screws 7 guided in arc-shaped slots in plate 2 concentrically around the axle 1 of the supporting plate for the record. Under the plate 2, supported against the top

plate *a* of the casing by a block 20, a plate 3 is held by screws 7 having a laterally projecting nose 22 engaging with a slot 4 of an angle piece 5 which carries in its free end the brake block 9 so that at the rotation of plate 3 the angle piece is shifted in longitudinal direction and at a sufficiently long stroke the brake block 9 acts upon the brake disc 8 of the centrifugal governor. In order to effect the rotation of the bearing 6 connected with the plate 3, a hollow body 12 is frictionally inserted in said bearing 6, said hollow body 12 having an extension 10 in which the operating lever 11 is mounted.

The operation is as follows:

In the position shown in Fig. 2 the axle 1 is freely rotatably. If braking has to be initiated it is merely necessary to slightly oscillate the lever 11 in clockwise direction, whereby, owing to the friction between the hollow body 12 and bearing 6 the plate 3 is rotated, the nose of which moves the angle piece 5, axially guided in longitudinal slots 21, together with the brake block 9 towards the brake disc 8, whereby retarding of the rotation of the supporting plate of the record is started which may be increased to stopping the latter. A special advantage of the mechanism is that it is not limited to a certain thickness of the wooden plates to the casing nor to a certain radius of the bottom plates of the driving mechanism as the hollow body 12 and the extension 10 can be inserted more or less deeply into the bearing 6. The regulating lever serves at the same time for locking and releasing the record plate axle thereby stopping and starting the driving mechanism without altering the setting of the centrifugal speed governor. The stopping and regulating of the driving mechanism is therefore obtained by one and the same lever.

The stopping of the motor is effected by the lever 11 which is adjustably connected to and guided on the extension 10 by means of a screw 13 so that it can carry out, besides the circular movement, a radial movement towards and away from the centre of the axle. On the hub of the record support T a spring *f* is arranged, one end *f'* of which projects outwardly and is adapted to be temporarily

engaged by the inner upwardly bent end 11a of the lever 11. By oscillating the lever 11 the speed of the centrifugal governor may be varied at will, through the block 9 being brought to bear on the disc 8 of the governor. If, however, the lever 11 is pushed radially towards the centre of the supporting plate its bent end 11a engages the projecting end f' of the spring f and the driving mechanism is stopped at once.

10 I claim:—

1. A speed governor for gramophones, comprising in combination with the centrifugal governor for the driving mechanism and with the vertical axle of the record plate, an adjustable angular lever, a brake block in the free end of said angular lever, a hollow body freely encircling said vertical axle, and a regulating lever shiftably mounted on said hollow body.

2. A speed governor for gramophones, comprising in combination with the centrifugal governor for the driving mechanism and with the vertical axle of the record plate, an adjustable angular lever, a brake block in the free end of said angular lever, an operating lever adapted to oscillate and to be shifted with regard to said axle, a bearing adjustably connected to said angular brake lever, a cylindrical body tightly fitting into said bearing, and means for adjustably connecting said cylindrical body to said operating lever.

3. A speed governor for gramophones, comprising in combination with the centrifugal governor for the driving mechanism and with the vertical axle of the record plate, an adjustable angular lever, a brake block in the free end of said angular lever, an operating lever adapted to oscillate and to be shifted with regard to said axle, a bearing adjustably connected to said angular brake lever, a cylindrical body tightly fitting into said bearing, means for adjustably connecting said cylindrical body to said operating lever, and a locking element on the hub of said record plate adapted to be stopped by said regulating lever being shifted radially in inward direction or released by said regulating lever being shifted radially in outward direction.

In testimony whereof I affix my signature.
OTTO KURZ.
